INVENTOR
F. A. FULLER
By
LESTER C. LIECHTER
ATTORNEY

UNITED STATES PATENT OFFICE.

FRANZ A. FULLER, OF NEWARK, NEW JERSEY.

MATCH BOX.

Application filed August 26, 1918. Serial No. 251,492.

To all whom it may concern:

Be it known that I, FRANZ A. FULLER, a citizen of the United States, residing in the city of Newark, in the county of Essex and State of New Jersey, have invented certain new and useful Improvements in Match Boxes, of which the following is a full, clear, and exact description, such as will enable others skilled in the art to which it pertains to make, construct, and use the same, reference being had to the accompanying drawings, and to letters of reference marked thereon, forming a part of this specification.

15 The present invention has reference to improvements in that class of match boxes described in my Patent No. 1,033,240, dated July 23, 1912, which are especially adapted for the reception of small packages of safety 20 matches made of card board, and such as have been in extensive use for advertising purposes, but which are also applicable to other uses.

The principal object of this invention is 25 to provide a neat, and simply constructed match safe or box of the general character stated, and the invention has for its further object to provide a match safe or box, comprising two normally closed sections, and a 30 guard pivotally arranged upon the hinge pin or rod of the case, so that the said guard, when in its normal position, is swung over, covers and protects the heads of the matches from being accidentally ignited when a 35 match is removed from the folder, and ignited upon the scratcher.

Another object of the invention is to provide a match safe or box of the character described, comprising two normally closed 40 sections, and a collapsible wind shield, arranged upon one of the sections near one end thereof.

A preferred embodiment of my invention is clearly illustrated in the accompanying 45 drawings, in which—

Fig. 1 represents a perspective view of the box.

Fig. 2 represents a plan view of the box open, the wind shield not being shown 50 in said view.

Fig. 3 represents an enlarged fragmentary

sectional side elevation of the box in its open position, said section being taken on line $x-x$ in Fig. 4.

Fig. 4 represents an enlarged end view 55 of the box.

Fig. 5 represents a fragmentary plan view of the box illustrating the wind shield in its closed position, secured near one end in one of the sections, and 60

Fig. 6 represents a fragmentary view in perspective of one of the box sections, illustrating the wind shield secured thereto, in its open position.

Similar letters of reference are used in all 65 of the above described views, to indicate corresponding parts throughout the specification and drawings.

The improved match box is preferably made of sheet metal of any suitable kind, 70 and comprising a box body a , and a suitably hinged lid b of substantially the same shape and dimensions. These parts are of such shape as to lend themselves readily to manufacture by the use of suitable punches and 75 dies, from ordinary sheet metal. $c-c$ represent lugs formed integrally with the front end of the box body a , extending downwardly into the box body in close proximity to and parallel with the front edge of the 80 box body a , thus providing a narrow space between which the free ends of the combined spring and catch member d are secured. These lugs $c-c$ extend inwardly from the longitudinal edges of the box body, so as to 85 partly overlie the package of matches contained by said box. The combined spring and catch member d is formed from a single flat piece of suitable metal, as illustrated, the ends of the spring being located between 90 the narrow space formed by the downwardly extending lugs $c-c$, and the front end of the box body flange. Formed centrally and integrally with the spring is an upwardly and inwardly extending tongue e , provided 95 with a projection f , to receive a holding lug g , formed integral with the lid b , so that when the box and lid are closed, such lug g will be received by the projection f and firmly secure the box members in locked 100 position. h represents a push piece secured to the underside of the spring in any con-

venient manner, adapted to pass through a suitable opening formed in the end of the box body *a*.

The box body *a*, and the lid *b* are respectively provided with one or more integral tubular members or ears *j*, *k*, and *l*, said tubular members *j*, *k* and *l* being adapted to dovetail together with the tubular members *m* and *n* of the guard *o*, to form a hinged barrel, all being operatively connected by means of a pin or pintle *p*.

The guard *o* is made from a single piece of metal, and along three of its side edges is provided with integral flanges *q* formed in the blank, from which said guard is made. The guard *o* is of such dimension as to properly overlie the heads of the matches as clearly indicated in the several views.

The rear or longitudinal edge of the guard *o* has formed integrally therewith, the tubular members *m* and *n*, which are formed by curling the metal thereof, as illustrated in the drawings.

The outer edge of the tubular member *n* and the inner edge of the tubular member *m*, of the guard *o*, as well as the right-hand edges of the tubular member *j* and the tubular member *l* of the box body *a*, are so formed as to provide integral stops, adapted to engage with each other to limit the movement of the guard *o* on the hinged pin or rod *p*, so that upon opening the case, the guard *o* will preferably assume the position illustrated in dotted lines, so that the matches may be easily and quickly removed from the folder and ignited upon the scratcher. By swinging the guard *o* into the position illustrated in dotted lines, it will not interfere with the ready insertion of the package of matches under the lugs *c—c*.

The wind shield which is secured near one end of the hinged lid *b* preferably comprises a flat plate *r* provided with integral ends *s—s* designed to receive rivets *t—t* by means of which the plate *r* is secured to the lid *b*. Hingedly connected to the front end of the plate *r*, in any suitable manner, is a plate *u*, the lower edge of which at its center is provided with a projection *v*, designed to engage with a centrally arranged spring *w*, formed integrally with the upper edge of the plate *r* which spring *w* is designed to maintain the plate *u* in the position illustrated, when the parts are in the position shown in Fig. 6 of the drawings.

Hingedly secured to the plate *u*, and to the plate *r*, are the collapsible side plates *y—y* and *z—z*, so constructed and arranged that the plates *z—z* will fold in and lie upon the plate *r* with the plates *y—y* resting upon the plates *z—z*, and under the plate *u* as illustrated in Fig. 5 of the drawings. In order to open the wind shield, it is only necessary to lift the plate *u* at its edge *u'*,

when the parts will spring into the position indicated in Fig. 6 of the drawings, and be maintained in that position by the spring *w* engaging with the projection *v* on the plate *u*. The plates *z—z* are slotted near their lower edges to receive the ends *s—s* of the plate *r*.

Experience has demonstrated that the organization above described is a practical and efficient one for accomplishing the ends sought by the invention. The construction, however, may be varied in detail without departing from the invention.

I claim:

1. A match box adapted to hold a package of paper matches, comprising a pair of hinged body sections, one of said body sections opposite the hinged end having means extending from its longitudinal edges into the box and adapted to partly overlie a package of matches contained by said box, a hinged one piece match guard pivotally connected with the hinge of said body sections designed to cover the match tops, the said guard being provided with means having engagement with the box hinge for limiting the movement of said guard.

2. A match box adapted to hold a package of paper matches, comprising a pair of hinged body sections, one of said body sections opposite the hinged end having means extending from its longitudinal edges into the box and adapted to partly overlie a package of matches contained by said box, a hinged one piece match guard pivotally connected with the hinge of said body sections designed to cover the match tops, the said guard and the said body section hinges being each provided with integral engaging stops having engagement with each other when the box is opened to carry the guard in one direction with one of said body sections and to limit the movement thereof.

3. A match box, comprising a box body and a hinged lid, said box body adapted to hold a package of paper matches, and having on its longitudinal edges integral holding pieces extending at right angles from said longitudinal edges into the box and adapted to partly overlie a package of matches contained by said box, the box body being further provided with tubular members having integral stops, a one piece match guard pivotally connected with the box body designed to protect the match tops, said match guard being provided with tubular members formed with integral stops designed to have engagement with the stops formed on the tubular members of the box body and adapted when the box is opened to carry the guard in one direction with the hinged lid and to limit the movement thereof.

4. A match box, comprising a box body and a hinged lid, said box body adapted to hold a package of paper matches, and hav-

ing on its longitudinal edges integral holding pieces extending at right angles from said longitudinal edges into the box and adapted to partly overlie a package of 5 matches contained by said box, the box body being further provided with tubular members having integral stops, a one piece match guard pivotally connected with the box body provided with integral edge flanges 10 and designed to cover the heads of the matches, the rear longitudinal flanged edge of said match guard being further provided with tubular members formed with

integral stops designed to have engagement with the stops formed on the tubular members of the box body adapted when the box is opened to carry the guard in one direction with the hinged lid and to limit the movement thereof. 15

This specification signed and witnessed 20 this 22nd day of August, 1918.

FRANZ A. FULLER.
